UNITED STATES PATENT OFFICE.

GEORGE W. WEBER, OF NEW YORK, N. Y., ASSIGNOR TO AMERICAN CAN COMPANY, OF NEW YORK, N. Y., A CORPORATION OF NEW JERSEY.

SARDINE-CAN.

1,030,358.

Specification of Letters Patent. Patented June 25, 1912.

Application filed June 29, 1907. Serial No. 381,500.

To all whom it may concern:

Be it known that I, GEORGE W. WEBER, a citizen of the United States, residing in New York, in the county of New York and State of New York, have invented a new and useful Improvement in Sardine-Cans, of which the following is a specification.

My invention relates to improvements in can closures, and more particularly to improvements in closures for cans having drawn or seamless bodies with covers secured thereto without soldering.

Heretofore in the practical use of sardine cans having drawn or seamless bodies, great difficulty is experienced in closing the cover on the can with the requisite hermetic tightness by double seaming or other seaming operation without solder, owing to the fact that the drawing operation necessarily puckers and roughens the surface of the externally projecting seaming flange on the can body, especially at the rounded corners of the rectangular sardine can, and also thins and frays the tin coating on the seaming flange and materially hardens and renders brittle the tin plate of such flange so that it is difficult to interfold the body flange with the cover flange into a smooth and perfect double seam with the several folds or thicknesses of the seam in the requisite tight, smooth, close metal to metal contact for the production of a hermetically tight seam without solder. And the difficulties in producing a hermetically tight seam are further increased by the fact that the operation of trimming the flange on the drawn body necessary to give such flange a uniform width throughout, also invariably leaves the flange at its extreme outer edge with more or less of a bur. And attempts have heretofore been made to somewhat lessen the percentage of leaky cans by applying to the seaming flange of the cover an elastic packing or gasket of rubber, paper, rubber cement and various forms of packing dope, the extreme outer edge of the seaming flange of the cover being turned down slightly to form a channel to receive such packing and partially protect it from danger of being injured, scratched or peeled off in shipment and handling of the cans. And such packing compositions applied to the cover flange may have proved of some

advantage in diminishing the percentage of leaky cans in cases where such packing coating happens to remain intact and not too much hardened, deteriorated or changed after being manufactured, and prior to the sealing of the cans and in cases where the heat of the cooking or processing step to which the cans are subjected after being double seamed does not cause the packing composition to too much soften and flow out from between the folds of the seam, or in cases where the internal pressure generated in the can during the cooking or processing step does not force openings through the softened packing.

I have discovered and demonstrated by my experiments, and herein my invention consists that the difficulties heretofore experienced may be practically overcome and the covers hermetically seamed and secured to the bodies of drawn or seamless sardine and other cans by interposing between the seaming flanges of the body and cover a soft metal packing fusibly united to the tin coating of the seaming flange of the body, the soft metallic packing being preferably of tin, and serving to partially fill up, smooth and obliterate the "drawing" puckers, creases or crevices and other irregularities in the seaming flange of the body produced by the drawing operation, and serving by its soft or yielding character when forcibly compressed by the double seaming tool or roller between the folds of the seaming flanges of body and cover to effectually close all leak producing crevices between the folds of the seam. The soft metal packing is preferably applied to the seaming flange of the body by passing the can bodies in an inverted position over a roller revolving in a path of molten or other soft metal, such, for example, as solder.

In the drawing, Figure 1 is a vertical section of a seamless or drawn sardine can embodying my invention. Fig. 2 is a horizontal section on line 2-2 of Fig. 1. Fig. 3 is a detail plan view of the drawn can body showing its seaming flange before having the soft metal packing applied and fusibly united thereto. Fig. 4 is a detail enlarged plan view showing a short portion of the seaming flange of the body before having the soft metal packing applied thereto.

Fig. 5 is a sectional view of the same. Fig. 6 is an enlarged plan view showing the seaming flange of the body after the soft metal packing is applied. Fig. 7 is a section on line 7—7 of Fig. 6. Fig. 8 is an enlarged detail section on line 8—8 of Fig. 9 showing a short length of the double seam to illustrate the function or action of the soft metal packing in effecting an hermetic closure, and Fig. 9 is an enlarged cross section of the seam.

In the drawing, A represents a drawn or seamless can body, the same being as illustrated in the drawing, of rectangular shape with rounded corners. The can body A has at its upper or mouth end an integral horizontally projecting seaming flange α , the same having the unavoidable drawing pockers, creases or irregularities α^1 therein, due to the drawing operation, some of which are comparatively coarse and others often very fine, but still sufficient, if not filled or closed to result in a failure in the hermetic tightness of the folded seam. The extreme edge of the seaming flange α also has to a greater or less extent the unavoidable bur α^2 at the extreme outer edge produced by the dies in trimming the seaming flange to give it a uniform width throughout as required after the drawing of the body A from the flat blank. The drawing operation also results in reducing the tin coating on the seaming flange at points to extreme tenuity and also materially hardens and renders brittle the seaming flange.

B represents the cover, the same being countersunk and having a countersunk wall b snugly fitting within the mouth or upper end of the can body A in tight frictional engagement therewith. The cover B also has a horizontally projecting seaming flange b^1 which is folded into a double or other seam with the seaming flange α of the body A.

C is a soft metal packing applied to the upper surface of the seaming flange α of the body and fusibly united with the tin coating thereof so that there is no chance or possibility for a leak between the packing and the body flange. The packing C may be of any suitable soft metal that will fusibly unite with the tin coating of the body flange α , but is preferably of tin. The soft metal packing C not only serves as a yielding or compressible packing between the folds of the seam but it also serves to effectually fill up, smooth out and obliterate the smaller drawing pockers, creases or irregularities produced by the drawing operation, and to materially round off the prominences and valleys of the larger pockers or irregularities in the cover flange and to supply thereto an excess of soft metal which under the pressure of the seaming roller will enable the several seam folds of the seaming flanges of the body and cover

to be brought into tight, close, metal to metal contact with each other, and thus produce an hermetically tight folded seam.

The soft metal packing is preferably applied and fusibly united to the seaming flange of the body by passing the bodies in an inverted position over rollers revolving in molten tin or other soft metal. The heating of the seaming flange in this soft metal coating operation also tends to materially anneal the same or reduce its hardness and brittleness resulting from the drawing operation.

The seaming flange b^1 of the cover is folded over the seaming flange α of the body and then the same are folded down snugly against the can body, thus producing a complete double seam of five walls or thicknesses, three of the interfolded walls being on the cover and two on the body.

I claim:—

1. A rectangular sardine can having rounded corners, and comprising a one piece seamless drawn tin plate body having an externally projecting seaming flange furnished with a solid impervious soft metal packing fusibly united to the tin plate coating thereof, said seaming flange being partially annealed or softened by the fusible application of said soft metal packing thereto, and a countersunk tin plate cover having a seaming flange interfolded with the seaming flange of the body into a double seam, said seaming flange of the body having the customary pockers and irregularities incident to its formation and said soft metal packing fusibly united to said flange filling, smoothing out and obliterating said pockers and irregularities to enable a tight joint to be formed therewith, substantially as specified.

2. The combination with a seamless drawn can body having an externally projecting seaming flange furnished with a solid impervious soft metal packing fusibly united thereto, said seaming flange being partially annealed or softened by the fusible application of said soft metal packing thereto, of a cover having a seaming flange interfolded with the seaming flange of the body into a hermetically tight seam, said seaming flange of the body having the customary pockers and irregularities incident to its formation and said soft metal packing fusibly united to said flange filling, smoothing out and obliterating said pockers and irregularities to enable a tight joint to be formed therewith, substantially as specified.

3. In a double seam can, the combination with a body having a seaming flange furnished with a solid impervious soft metal packing fusibly united thereto, said seaming flange being partially annealed or softened by the fusible application of said soft

metal packing thereto, of a cover having a seaming flange interfolded with the seaming flange of the body into a double seam, said seaming flange of the body having the 5 customary puckles and irregularities incident to its formation and said soft metal packing fusibly united to said flange filling, smoothing out and obliterating said puckles and irregularities to enable a tight joint to be formed therewith, substantially as 10 specified.

4. A tin plate can body having a seaming flange adapted for double seaming with a cover flange and furnished with a solid impervious soft metal packing fusibly united to the tin coating of the upper surface of 15 said flange, said seaming flange being partially annealed or softened by the fusible application of said soft metal packing thereto, said seaming flange of the body having the customary puckles and irregularities incident to its formation and said soft metal packing fusibly united to said flange filling, smoothing out and obliterating 20 said puckles and irregularities to enable a tight joint to be formed therewith, substantially as specified.

and irregularities to enable a tight joint to 25 be formed therewith, substantially as specified.

5. A tin plate seamless drawn rectangular can body having rounded corners and a projecting flange adapted for double seaming 30 with a cover flange and furnished with a solid impervious soft metal packing fusibly united to the tin coating on the upper surface of said flange, said seaming flange being partially annealed or softened by the 35 fusible application of said soft metal packing thereto, said seaming flange of the body having the customary puckles and irregularities incident to its formation and said soft metal packing fusibly united to said 40 flange filling, smoothing out and obliterating said puckles and irregularities to enable a tight joint to be formed therewith, substantially as specified.
